UNITED STATES PATENT OFFICE.

WILLIAM H. HOOPER, OF SALEM, MASSACHUSETTS, ASSIGNOR TO UNITED SHOE MACHINERY COMPANY, OF PATERSON, NEW JERSEY, A CORPORATION OF NEW JERSEY.

MACHINE FOR TREATING BOOTS AND SHOES.

1,161,936.

Specification of Letters Patent. Patented Nov. 30, 1915.

Application filed July 25, 1912. Serial No. 711,571.

To all whom it may concern:

Be it known that I, WILLIAM H. HOOPER, a citizen of the United States, residing at Salem, in the county of Essex and State of Massachusetts, have invented an Improvement in Machines for Treating Boots and Shoes, of which the following description, in connection with the accompanying drawings, is a specification, like letters on the drawings representing like parts.

The invention to be hereinafter described relates to machines for treating boots and shoes, and more particularly to such machines where the boot or shoe is mounted or sustained upon a support during the action of a tool thereon.

In machines of this general type it is desirable upon the completion of the proposed operation on a boot or shoe that the machine be automatically brought to rest. Difficulty has been experienced in some cases, however, in effecting an interruption of the operative relation of parts on the train of mechanism at the instant when the machine is to be stopped, with the result that the machine has not always acted as intended, or some portions have been broken, or subjected to excessive wear and strain.

With these and other facts in view, the present invention aims to provide means, whereby preliminarily to or at the time of the operation of the stopping means, the strain of driving engagement of some portion of the train of mechanism will be relieved, thereby facilitating the action of the stopping means, all of which will best be made clear from the following description and accompanying drawings of one form of means for carrying the invention into practical effect, it being understood that the invention is not restricted to the particular means shown, but may be variously modified or changed within the scope of the actual invention which is defined by the claims.

In exploitation and explanation of the invention, it has been shown as applied to a laying or leveling machine, and more especially to such type of machine as shown and described in application Serial No. 454,082, filed September 21, 1908, but it is to be understood that it is not necessarily restricted thereto and may be employed in other ma-

chines either of that or different type, wherein the boot or shoe is sustained by a work-support during the action of a tool. 55

In the drawings:—Figure 1 is a vertical longitudinal sectional elevation of a machine embodying the present invention; Fig. 2 is a detached detail, partly in section, showing a clutch controller and associated parts; Fig. 3 is an enlarged detail typifying the cooperative relation of the work-supporting lever and the cam for acting thereon; and Fig. 4 is an enlarged sectional elevation of the clutch mechanism and associated parts, 65 certain portions being broken away to show details.

The machine frame may be of any appropriate character to support the operating parts, and, as shown, comprises standards 70 or uprights 1, upper and lower cross-beams 2 and 3, rearwardly extending braces 4, and suitable tie rods 5, extending between the cross-beams 2 and 3 and connected to the said cross-beams by suitable nuts 6, said tie 75 rods serving as guides for the shoe support in its rising and falling movements as will more fully appear.

Mounted in appropriate bearings in the machine frame is the driving shaft 7, which 80 may be driven by the pulley 8, deriving motion from a suitable source of power, substantially as pointed out by said prior application. Said driving shaft 7 is operatively connected to a shaft 9, as by the gear connection 10 and 11, indicated by dot and dash lines in Fig. 1, and for the purpose of identification, said shaft 9 may be hereinafter referred to as the clutch shaft, the construction being such that said driving and clutch shafts may be continuously driven when the former is operatively connected to the driving power. 85

The present form and embodiment of the invention contemplates the provision of twin 95 machines on the one frame, that is there may be two similar operative devices which, for convenience and economy, may be alternately operated, so that while the operator is adjusting a boot or shoe to the work support of one machine, the other may be treating a shoe previously supplied, and as said twin machines are or may be alike, a description of one will be sufficient, it being under- 100

stood also that one machine alone may be employed, if desired.

Loosely mounted on the clutch shaft 9 are the two similar gears 12, 12, each of 5 said gears being held from longitudinal movement by suitable means, such for instance, as a sleeve or bushing 13 secured to the shaft by a pin 14 and engaging a collar 15 between itself and a bearing 16, said 10 collar being loose on the shaft and connected to the gear 12 by suitable means, such as the screws 17. Obviously other expedients may be employed for loosely mounting the gears 12 upon the clutch shaft.

15 Each of the gears 12, Fig. 4, has a hub 18, the face of which constitutes one member of a clutch, the other member being formed by a part 19 splined to the clutch shaft, and having a circular recess 20 engaged by a 20 roller 21 carried by an arm of a bell crank lever 22, pivoted at 23 to a bracket or part 24 of the machine frame. A spring 25 disposed between the clutch members 19, normally tends to move them into engagement 25 with their coöperating clutch members 18, when said clutch members 19 are free to move.

Each of the bell cranks 22 has a tail piece 26 to which a spring 27 is connected, said 30 spring tending to hold the arm 28 of the bell cranks against the periphery of a clutch controller 29 provided with raised and depressed portions 30 and 31 respectively, Fig. 2. Obviously when the end 28 of a bell 35 crank lever rests upon a raised portion 30 of the controller, the connected clutch member 19 will be held out of engagement with its coöperating member 18, and when the end 28 moves into a depressed portion 31 of 40 the controller, the spring 25 will be permitted to move the clutch members into engagement. If at this time the high parts of the clutch faces are opposed to each other, however, the member 19 cannot move longitudinally of the clutch shaft until the latter 45 has been rotated to carry the high parts of the clutch members from opposed relation. The bell crank 22, however, is under the influence of the spring 27 which maintains the 50 end 28 on the clutch controller, and such turning movement is permitted under the conditions noted by making the circular recess 20 of increased width, as shown.

The clutch controller 29 is mounted upon 55 a stud 32, Figs. 2 and 4, secured to a bracket or arm 33 connected to the machine frame, and has formed as part of said controller or secured thereto, a ratchet wheel 34, which is actuated by a pawl 35 carried by an arm 36 60 projecting from a hub 37 mounted on the stud 32, a spring 38 (Fig. 2) normally acting to hold the pawl in engagement with the teeth of the ratchet. Jointed to the pawl arm 36 is a rod 39, which leads to the front 65 of the machine where it is jointed at 40 to

an arm 41 rising from the treadle 42, Fig. 1. A spring 43 normally holds the treadle raised and the said rod 39 pushed rearwardly, the pawl 35 at such time being in engagement with one of the teeth of the 70 ratchet 34 and in position to turn the same the desired distance when the treadle is depressed.

Pivotedly mounted at 44, Fig. 4, on the bracket or arm 33 is a yielding locking arm 45 carrying a roller 46 adapted to engage depressions in the clutch controller and yieldingly lock the same from rotation in either direction, but yet permit the ratchet to turn the controller when actuated by the 80 treadle, as already described. To cause this yielding lock action, the arm 45 is engaged by a spring 47, the opposite end of said spring being secured to a fixed part of the machine frame and normally acting to hold 85 the roller 46 against the periphery of the controller, the ends of said spring being clearly indicated in Fig. 4, all as fully disclosed in Patent No. 1,041,668.

From the construction thus far described, 90 it will be apparent that upon depression of the treadle, the pawl 35 will rotate the ratchet 34 and turn the clutch controller a suitable distance to cause its raised and depressed periphery to act upon the arm 28 of the bell crank so that, assuming the arm 28 to be resting on a raised portion of the clutch controller in which position the clutch members are disengaged and the treadle to be depressed, then the clutch controller will 1 be moved to permit the end of the arm 28 to drop into a depressed portion of the controller, whereupon the clutch members become engaged and the connected gear 12 rotated. The above is a good and practical 10 form of starting device, but it is to be understood that the invention is not restricted thereto and that various expedients may be employed under the control of a treadle or other manually operated device to engage 11 parts of the train of mechanism which give to the machine its operative action.

Mounted on a shaft 48, Fig. 1, is a cam-faced gear 49, meshing with the smaller gear 12 on the clutch shaft so that when the gear 12 is rotated, as hereinbefore explained, it imparts rotation to the cam gear 49 from which some of the characteristic motions of the parts of the machine are derived, as for instance, is clearly set forth in the application to which reference has been made. It is sufficient at this time to state that when the cam gear 49 has made one complete rotation from a point somewhat in advance of that indicated in Fig. 1, one full cycle of the 12 machine operation has been made, and it is then desirable to bring the parts to rest automatically. To secure this automatic stopping of the machine, the cam gear 49 has pivotally mounted thereon at 50, Fig. 1, a 13

trip finger 51 having a tail piece 52 normally held against a stop-pin on the face of the gear by a spring 53, the free end of the trip finger at such times projecting so as to engage a recess 54, Fig. 2, in the periphery of the clutch controller. From this it will be clear that as the cam gear completes its rotation under the actuation of the gear 12, the end of the stop finger will engage a recess in and turn the clutch controller to cause a high part thereof to pass beneath the end of the arm 28 of the bell crank and, perforce, move the connected clutch member out of engagement with its coacting member, thus stopping the machine, substantially as pointed out in the application to which reference has been made.

In the character of machine illustrated, there is mounted near the top thereof a former and its actuating devices, identified as a whole in Fig. 1 by A, said former being provided with a patterned surface generally complementary to the surface of the shoe sole to be treated, although this character of former is not essential; and opposite thereto is the coacting shoe support, generally designated by B, said former and shoe support being adapted for certain relative movements to effect the proper laying and leveling of a shoe sole, all as clearly pointed out in the application mentioned.

Guided for rising and lowering movement in the machine frame is the shoe support, Fig. 1, which may comprise a table 55 having appropriate side bearings sliding on and guided by the tie rods 5.

Mounted upon the table 55 is the jack 56 which may be of any appropriate character for supporting or sustaining a shoe during the action of the tool or former thereon, and said jack, as pointed out in said application, may have appropriate movement imparted thereto lengthwise of the table.

The shoe support comprising in the present form of the invention, the table 55 and its jack 56, is appropriately connected to the arm 57 of a lever pivoted at 58 at the lower part of the machine frame, the other arm 59 of said lever being provided with a roll 60 traveling on the periphery of a cam 61 carried by the cam gear 49, as clearly indicated by Fig. 1 of the drawings, and as fully pointed out in the application heretofore mentioned. The shoe support may be connected to the arm 57 of said lever in any approved manner, as by the rod 62, shown by dotted lines in Fig. 1, jointed to the arm 57 of said lever substantially as pointed out in the application mentioned, and since these features of construction form no essential part of the present invention, and are well understood by those skilled in the art, it will be sufficient to note that the shoe support comprising the parts noted, is sustained by the arm 57 of the said lever and that it

is given its characteristic upward and downward movement by means of the cam 61 on the cam gear 49.

From the construction described as one embodiment of the present invention, it will be noted that upon depression of the treadle 42, the operation of the machine is started, the gear 12 on the cam shaft turning the cam gear 49 and raising the shoe support through the connections described, to bring the latter into operative relation with the tool or form. When the machine has made its cycle of operations the finger 51 meets and actuates the clutch controller to cause the machine to come to rest. At this time, however, if the driving strain between the engaging portions of the clutch members is maintained, difficulty will be experienced in disengaging the clutch members, and the present invention contemplates the provision of means for relieving the driving stress between the clutch members preliminarily to or at the time when the machine is to be stopped, so that the clutch members may be readily disengaged, and in the form of the invention herein illustrated, advantage is taken of the weight of the shoe support to ease the stress between the engaging parts of the clutch members, as will now be described.

By reference to Fig. 1 it will be noted that the cam gear 49 rotates clockwise during the cycle of machine operation and that the high portion of the cam 61 presents a dwell for holding the shoe support in raised position for the action of the laying and leveling form upon the sole of a shoe mounted on said support, and that upon the completion of the laying or leveling action the low part 62 of the cam 61, acting through the lever described, permits the shoe supports to move downward, the weight of the shoe support, however, being still sustained from said cam through said lever. When the shoe support has been thus lowered and the jack moved outward or to the front of the machine for removal of the treated shoe, it is desirable that the stopping devices act to stop the machine, and to relieve the driving strain between the clutch members at this time, the cam 61 is provided with a part 63, so inclined with respect to the low portion of the cam that the weight of the shoe support acting through the arm 59 of its supporting lever imparts to the cam gear 49 a forward impulse in the direction of its rotation thereby relieving the driving strain between the engaging portions of the clutch members so that their disengagement may be readily effected and the machine brought to rest.

It will be noted by viewing Fig. 1 and Fig. 3 that the roll 60 on the shoe supporting lever arm 59 acts upon the incline 63 just prior to or substantially at the time that the finger 51 acts to turn the controller to effect

machine stoppage, so that at the moment the clutch members are to be separated the cam gear 49 is given a forward impulse under the weight of the shoe support and the driving strain between the members of the clutch is relieved thus facilitating the action of the stopping means.

While the invention has been exploited herein in connection with a laying or leveling machine it is obvious that it is not limited to such machine, but is applicable in any shoe treating machine where the shoe support is sustained during the action of the tool and its weight is applicable for imparting a relieving impulse to the train of driving mechanism that their operating relation may be interrupted.

What is claimed is:—

1. In a machine for treating boots and shoes, the combination of a shoe support, a tool for acting on a shoe sustained by said support, stopping means for the machine including clutch members, and means for causing the weight of the shoe support to ease the operative engagement of the clutch members when they are to be disengaged.

2. In a machine for treating boots and shoes, the combination of a shoe support, a tool for acting on a shoe sustained by said support, means including relatively movable members for stopping the machine, and means operative through the shoe support when the machine is to be stopped to enable the said members to be relatively moved.

3. In a machine for treating boots and shoes, the combination of a shoe support, a tool for acting on a shoe sustained by said support, driving means for the machine, means for disengaging the driving means from operative relation with the machine to stop the same, and means acting automatically as the machine approaches the stopping point for easing the driving engagement of the driving means with the machine to facilitate its disengagement therefrom.

4. In a machine for treating boots and shoes, the combination of a shoe support, a tool for acting on a shoe sustained by said support, driving means for the machine,

automatic means including relatively movable members for stopping the machine, and means operative under the weight of the shoe support for facilitating the relative movement of said members when the machine is to be stopped.

5. In a machine for treating boots and shoes, the combination of a shoe support, a tool for acting on a shoe sustained by said support, driving means for the machine, manually controlled means for starting the machine, automatic means including relatively movable members for stopping the machine, and means for easing the driving engagement between parts of the driving means as the machine approaches the stopping point to facilitate their disengagement.

6. In a machine of the character described, the combination of a tool, a shoe support, means for causing relative approach of the tool and shoe support, and permitting separation thereof, driving means for the machine, means for disconnecting the driving means from operative relation with the machine, and means operative by movement of the shoe support for easing the driving connection of the driving means with the machine that disconnection of the driving means with the machine may be effected.

7. In a machine for treating boots and shoes, the combination of a tool, a shoe support for sustaining a shoe for the action of the tool, driving means for the machine, stopping means for disconnecting the driving means from operative relation with the machine, and means connected to and operated by the shoe support when the machine is to be stopped for easing the driving connection of the driving means with the machine that disconnection of the driving means with the machine may be effected by said stopping means.

In testimony whereof, I have signed my name to this specification, in the presence of two subscribing witnesses.

WILLIAM H. HOOPER.
